AUTOMATIC PHONOGRAPH

Edward E. Collison and Ralph R. Erbe, Fort Wayne, Ind., assignors to The Capehart Corporation, Fort Wayne, Ind.

Application September 9, 1931, Serial No. 561,898

21 Claims. (Cl. 274—10)

This invention relates to new and useful improvements in automatic record changing phonographs wherein a plurality of records of either the conventional ten and twelve-inch size may be 5 played, reference being particularly made to the co-pending application of Erbe, Serial No. 394,981, filed September 25, 1929.

As disclosed in the above mentioned application, the conventional ten and twelve-inch records may be promiscuously placed in the magazine whereupon the machine will reproduce them irrespective of size. Furthermore, the machine may be adjusted to play a record on first one 10 side and then the other before returning it to the magazine; play it on one side and then return it to the magazine, and after the succeeding records have been played, play the same on the opposite sides thereof; or it may be adjusted so as to repeat a record.

One feature of the present invention as distinguished from that disclosed in the above co-pending application resides in the construction and arrangement of the magazine whereby a twelve-inch record may be readily released therefrom while ten-inch records will be supported therein as will be more specifically hereinafter set forth. This eliminates any difficulty in respect to handling any quantity of records of either the ten or twelve-inch size, within a pre-determined limit.

Another feature of the invention resides in the automatic stop for placing the record changing mechanism in operation upon completion of a record. By means of the stop disclosed herein, more positive action of the mechanism for starting the record changing is accomplished irrespective of whether the record grooves terminate in an eccentric or spiral groove, i. e., the same mechanism operating for either type, whereas heretofore it has been the practice to use one mechanism for a spiral groove and another mechanism for an eccentric groove. As will be herein-after set forth more in detail, the stop mechanism is actuated by a variation in the inward movement of the reproducer from its movement during the reproduction. Thus, during one revolution of the turntable, if the spiral, eccentric, or any other type of groove causes the reproducer to move inwardly beyond the pitch of the reproducing grooves, the mechanism is actuated.

A further feature of the invention resides in the means for positioning the reproducer arm at the beginning of a record of any size,—such as 55 a ten or twelve-inch record is a simple and pos-

tive manner as will be hereinafter set forth. Associated therewith is means for frictionally moving the reproducer toward the periphery of the record for engagement at the beginning thereof as distinguished from the usual spring 5 for accomplishing this purpose. Thus, the arm is swung inwardly to the record with a positive action under control of the friction mechanism whereas with the usual spring for returning the reproducer there is no positive control therefor. 10

A further feature of the invention relates to the means for positively setting the records in position to be ejected from the magazine, whereby the ejecting device will at all times have a record in position to eject regardless of the number of records in the magazine.

Still a further feature of the invention resides in the control mechanism for manually adjusting the same for playing both sides of the record before returning to the magazine, playing one 20 side thereof and returning it to the magazine, or repeating the record as will be hereinafter set forth.

Still a further feature resides in the provision of means for feeding the reproducer from the 25 smooth peripheral edge of the record into the beginning of the reproducing grooves with a positive movement. This is accomplished by means of a brush which immediately engages the reproducing grooves upon the reproducer being lowered into record engaging position, said brush acting to cleanse the grooves and at the same time gradually draw the reproducer into groove engaging position with a steady and governed movement, as distinguished from the usual free 30 sliding uncontrolled movement as heretofore.

The full nature of the invention will be more clearly understood from the accompanying drawings and the following description and claims:

Fig. 1 is a side elevation of the record changing machine showing parts thereof in section. Fig. 2 is a view taken on the line 2—2 of Fig. 1 with the records removed. Fig. 3 is a plan view with a portion of the turntable removed and with the record magazine removed. Fig. 4 is a sectional view of the control for the record changing mechanism. Fig. 5 is a front elevational view of the lower portion of the mechanism. Fig. 6 is a plan view of a portion of the turntable with record and reproducer. Fig. 7 is the same as Fig. 6 showing a side elevation thereof. Fig. 8 is an enlarged view showing the side elevation of the reproducer. Fig. 9 is a front elevation thereof. Fig. 10 is a sectional view of the cam showing the associated parts forming part of the re- 55

versing mechanism. Fig. 11 is a detail drawing of the clutch operating mechanism. Fig. 12 is an enlarged diagrammatical illustration of the various positions of the control lever. Fig. 13 is an enlarged view of the record releasing lever. Fig. 14 is a top plan view of the operating mechanism with the supporting plate and top structure removed.

Referring in detail to the drawings, at 20 is shown a base or supporting plate having depending bearing portions on which various parts of the mechanism are mounted. Disposed on a support 21 below the base or plate 20 is an electrical motor 22 to which current is supplied from any suitable source through the wires or conductors 23.

This motor, either by direct drive or through gearing if desired, drives the vertically extending spindle 24 which extends upwardly through the base or plate 20 and carries at the upper side of said plate a turntable or other record support 25. It will be obvious that since the spindle is an integral shaft, the turntable 25 will be driven as long as the motor 22 is in operation.

25 A reproducer 26 is used for taking the recorded matter from the records supplied to the turntable 25. This reproducer is pivotally mounted for movement in a vertical plane, on screws or other bearing means 27 carried by the arms 28 of a reproducer arm 29. Arm 29 is mounted for movement in a horizontal plane over the record and when the stylus 30 of the reproducer 26 has been brought into engagement with a record, the reproducer and arm 29 are fed across the record by contact of the stylus with the record groove. Means are provided for elevating the stylus and swinging the reproducer arm to position the stylus for engagement with the beginning of a record, as will later be described in detail.

40 Means are provided for supporting a plurality of records, and for feeding them one at a time to the turntable 25. This means includes a bracket 31 secured to the base or plate 20 as by screws 32, said bracket having a pair of upwardly curved spaced arms 33 connected and braced by a web portion spaced above the base portion 35 of the bracket. At their upper ends the arms 33 are enlarged and provide bearings 36 for short shafts or studs 37 of a record magazine or rack 38. The rack 38 is pivoted in the bearings 36 for a swinging movement.

The rack 38 is of a size to receive records of various diameters, the most common size records 55 at the present time being those in the neighborhood of a diameter of ten inches and those having a diameter of approximately twelve inches.

Rack 38 includes a forwardly projecting flange 39, back portion and a lower cross bar 41 connecting the lower ends of the side portions of the flange 39. A sectional view of the cross bar 41 is shown in Fig. 1, and it will be apparent that this bar is an angle bar having a substantially horizontal portion and a substantially vertical portion. Carried by the cross bar 41 at points equally spaced from its center, are a pair of forwardly projecting pins 44 disposed to be engaged by the lower edge of a group of records to support the weight of the records in the magazine. 65 These pins may be notched near their forward ends to prevent records slipping off of them.

70 Formed on or secured to the back of the rack 38 are pairs of ribs 47 and 48. The rear record of those in the rack will have its upper portion 75 in engagement with the ribs 48 when the records

are stored. These ribs 48 function in the transfer of a record from the rack to the turntable 25 as will be later more fully described.

Means are provided for transferring records one at a time from the rack or magazine 38 to the turntable. The first step in this operation is the separating of a record from the group of records. This requires the co-operation of the motor. A pair of clutch elements 49 and 50 are disposed about the vertical turntable spindle 24, 10 and while the clutch element 49 is keyed to the spindle to turn with it, the clutch element 50 is free on the spindle, and normally remains stationary while the spindle revolves in it.

These clutch elements are held disengaged by 15 the lever 52 pivoted to the bracket 53 of plate or base 20 as at 54, said lever being normally held in position to maintain the clutch elements in disengagement by the spring 55. The opposite end of lever 52 includes a yoke portion having 20 a pair of fingers or pins disposed in a clutch 57 of the clutch element 49. The free end of said lever carries a core 56 of a solenoid coil 58, which, when energized, attracts the core, rocking lever 52 about its pivot 54 against the tension of the 25 spring 55 and moving clutch element 49 into clutching engagement with the clutch element 50.

With the clutch elements 49 and 50 in engagement, clutch element 50 is driven by the motor 22, which, in turn, drives the worm 59, meshing 30 with a worm wheel 60 secured to the drive shaft 61.

Upon the shaft 61 making one complete revolution, during which time the solenoid 58 has become deenergized, the trip 42 is brought into 35 engagement with the pin 43 to push the rod 45 upwardly, said rod being pivotally connected with the lever 52. Thus, the lever 52 is positively forced upwardly so as to cause the clutch members 49 and 50 to become disengaged upon 40 completion of one revolution of the shaft 61. Inasmuch as the record changing mechanism has completed its work after the one revolution, it is thereupon held inoperative since the spring 55 will normally hold the lever 52 and clutch members 45 out of engagement so that only the turntable is driven by the motor.

Secured to the shaft 61 is a large cam 62 having in its sides cam tracks or grooves to be described, and having on its periphery a cam 63 50 for operating a mechanism to chop or remove a record from the rack 38. A reversely curved lever 64 is pivoted intermediate its ends as at 65 to a depending bracket 66 carried by the plate or base 20. At one end lever 64 carries a roller 55 67 for engagement with the periphery of the cam wheel 62 and cam 63 when it is desired to feed a record from the rack 38 to the turntable 25.

The opposite end of lever 64 is pivotally connected to an upright rod 68 passing through the 60 base or plate 20 and through a guide means 69 secured to the upper side of the said base or plate. At its upper end the rod 68 is bent forwardly and its forward portion 70 passes through an elongated opening 71 in a knife or chopping 65 lever 72. This lever 72 is pivoted intermediate its end at 73, to the cross bar 41 of the rack 38.

One end of the lever 72 extends between the supporting pins 44 and 45, and this end 74 of the lever lies closely against the vertical portion 70 43 of the angle bar 41. The rear surface of the portion 74 of lever 72 inclines downwardly, and the central portion of the vertical part of cross bar 41 is scooped out or cut away. The last record of a group of records in the rack rests on 75

the portion 74 of lever 72, the rear of the lower edge portion of this record being in engagement with the vertical portion of the cross bar.

The portion 74 of the lever 72 is provided with a hook 74a which engages the three next records adjacent the record to be ejected, carrying said last three records upwardly. As it lifts, the record will be ejected and drop over the bar 41. The hook portion 74a slopes toward the portion 10 74 so that the three records engaged thereby are caused to slide rearwardly as they are elevated. This is for the purpose of moving the records in the rack rearwardly as each record is discharged so that the most rearward record will always be 15 positioned for engagement and discharged by the portion 74 of the lever 72. This avoids the danger of there being so few records in the rack that they will not slide back into discharging position.

20 Now, when the cam 63 strikes the roller 67, lever 64 will be rocked on its pivot 65 drawing downwardly on the rod or upright 68, rocking lever 72 about its pivot 73 to elevate the end portion 74 of lever 72. This operation of course elevates the last record in the rack, and owing 25 to the incline of the rear of knife portion 74 and the cut-away portion of bar 41, the record slides downwardly out of the rack and lands with its lower edge resting on spaced cushioning pads 75.

25 The next step is to move the record from the pads 75 to the turntable. To accomplish this, the cam wheel 62 is provided with a cam groove 76 in which is disposed a pin 77 carried by an arm 78 slotted at its lower end as at 79, the slot receiving the shaft 61. At its upper end, the member 78 is pivotally connected as at 80 to a lever 81 secured at its upper end to a shaft 82 supported by brackets depending from the lower side of the plate 20. Also secured to the shaft 40 82 is a segmental gear 84 spaced along the shaft from the lever 81 and having teeth in mesh with a segmental gear 86 formed on the underside of a rearwardly extending tongue or projection 87 of a record carrying and guiding means or pan 88.

45 This pan 88 is pivotally mounted on brackets 89 projecting upwardly from the plate 20, and is adapted to be swung on said pivotal mounting through an arc from the full line position to a dotted line position surrounding and below the turntable 25. When a record has been removed from the group and is resting on the pads 75, the rearwardly extending tongue portion 87 of pan 88 is disposed below these pads, the pan 88 being in the full line position of Fig. 1. As the pan swings downwardly on its pivot 89 toward the dotted line position, the tongue or extension 87 swinging upwardly between the pads 75, engages the lower edge of the record and elevates it.

50 As illustrated in Fig. 2, the pads 75 are mounted in a well below the plane of the plate 20, said pads being separated to permit the tongue 87 to pass between them to a lower level so that as it is caused to rise, it will be below the bottom edge of the record supported by the pads which it will engage and elevate upon the downward movement of the pan 88. As shown in Figs. 1 and 2, the rack is provided with an inwardly directed tongue 39a extending downwardly from the top portion thereof sufficient to permit the top edge of either the ten or twelve-inch records to rest thereagainst when supported in the rack. When the ejected record is dropped onto the pad 75 in the well as shown in Fig. 1, it falls

below said tongue out of engagement therewith so that the upper edge of the ejected record bears against the felt cushion 39b while it is supported against the upwardly extending support 39c at the bottom thereof.

5 Said support 39c is rigidly mounted upon the plate 20 at the rear of the magazine as shown in Figs. 1 and 2. Upon the record being elevated as above described by the tongue 87, the ejected record will be pushed upwardly into the pocket 10 formed by the tongue 39a entirely free from the records in the rack so that it may be freely caused to slide onto the turntable as hereinafter set forth.

15 As the pan 88 moves downwardly, the rack 38 is swung in the bearings 36 toward the turntable to slide a new record thereon. For the purpose of swinging the rack through this arc, the cam 62 is provided with a cam groove 90 in which operates a pin 91 slidably mounted in a 20 block or enlarged portion 92 of a slidable beam 93. When the pin 91 is in the groove 90, the device is operating to supply a record to the turntable.

25 Movement of the cam produces a sliding movement of the beam 93, the beam having a slot 94 through which the shaft 61 passes. At its upper end the beam 93 is pivotally connected to one arm of a bell crank lever 95 pivoted as at 96 on the bracket 97 depending from the plate 20. 30 The opposite end or arm of bell crank 95 is pivotally connected as at 98 to a link 99 pivotally connected at its upper end to a bracket 100 rigidly secured to the rack 38. It will be apparent that the bracket 100 is disposed on the rack 38 35 rearwardly of the pivot studs or shafts 37, and that when the member 93 is moved forwardly by engagement of the pin 91 in the cam groove 90, the bell crank lever 95 will be rocked, and operating through the link 99, will rock the rack 38. 40

The rack 38 is, of course, swung on its pivot after a record has been chopped out of the rack and after the tongue or extension 87 of pan 88 has engaged and elevated the record from the pads 75. The rear portion or back 40 of the rack 45 38 flares outwardly as at 102, and the upper portion of the record being moved is, of course, in contact with the back of the rack.

50 Now, as the pan 88 moves downwardly on its pivots, the record slides forwardly on the pan, and movement of the rack 38 assists in the initial forward movement of the record and maintains one edge of the record elevated, as the other edge extending through the pan engages and slides across the surface of the turntable. The turntable is revolving, but the record is held from lateral movement due to the revolving of the turntable, owing to the fact that the edge of the record is in engagement with the inner edge of the pan.

55 60 If a ten-inch record or a record of small diameter is being placed on the turntable, its forward edge will engage against the vertical wall 103 of the pan, and its further forward movement will be stopped. Now, as the rack 38 swings back, the cam 62 having completed one-half of a revolution, the rear edge of the records is gradually lowered (as the flared portion 102 moves from under the record) into position, the front edge of the record being engaged and stopped by the wall 103 of the pan, whereby the record is let down properly centered on the turntable.

65 70 75 By way of explanation it may be noted that the edge of the record comes into engagement with the turntable on the opposite side of the

center pin from that at which the rack 38 is located. Further, the turntable is covered with some smooth surface material as "bakelite" in order that there will be no difficulty in sliding the record across it. This material gives sufficient traction and the record does not slip on it when in playing position.

When records of larger diameter are to be played, they slide over the wall 103 owing to their large diameter, and their forward edges contact with the wall 106, the arc of which is struck on a radius equal to the radius of a record of large diameter. This wall 106 limits the forward movement of a record of large diameter, and as the rack 38 swings back to the position illustrated in Fig. 1, the record of large diameter is let down onto the turntable properly centered.

After the record is positioned on the turntable, the arm 29 is swung to position the stylus 30 at the beginning of the record. As will later be explained in detail, at the end of a record this arm 29 is elevated and swung to carry the reproducer 26 beyond the periphery of the record. The elevating means for this purpose comprises a cam 107 having a notch or depressed portion in which the lower end of an extension 110 of a rod or shaft 111, attached to or formed with the lower end of the arm, rests.

Disposed about the shaft 111 is a collar 114 between the upper flange 115 of which, and the plate 20, is disposed a coil spring 116. The coil spring surrounds the shaft 111 and obviously will be compressed on the collar 114 being elevated. A second collar 117 surrounds the extension 110, and is keyed to turn with it, but is slidable along the extension. A light coil spring 118 is disposed between the collars 114 and 117, and about the extension 110 of the shaft 111.

Rigid with the collar 117 is a bent rod 119 including a horizontal portion and a depending portion. Secured on the shaft 61 adjacent the cam 107 is a second cam 125 including an arcuate portion, an upstanding arm 127 and a lateral flange or wing 128. The portion forming the arm 127 and wing 128 is secured to the arcuate portion.

Assuming that the clutch elements 49 and 50 have been brought into engagement, shaft 61 will be driven as previously described, and during the first part of its movement, cam 107 will cause the extension 110 of shaft 111 to ride upwardly out of the notch 109 compressing the springs 116 and 118. As extension 110 reaches the high point of the cam, the reproducer and stylus have, of course, been so elevated that the stylus is no longer in contact with the record.

At this time arm 127 also turning with the shaft 61, engages the substantially horizontal portion 120 of rod 119 forcing the rod to move in an arc, the center of which is the extension 110. This movement of the rod is transmitted by collar 117, extension 110, and shaft 111 to the reproducer arm, swinging the reproducer to a position beyond the edge of the record. Spring 116 being compressed, frictionally resists this movement, prevents the arm 29 from being thrown outward with a sudden uncontrolled movement, and results in the arm being given a steady outward movement by continual contact with the cam.

After the rod 119 has been moved outwardly a predetermined distance, it moves out of the range of the arm 127. At this point rod 119 will be engaged by the arcuate surface of the cam 125 which will serve to hold the rod in its outermost position during the time it is in contact with said

surface. It will be understood that the cams are continually turning, and when the end of said arcuate surface is reached, the wing or lateral portion 128 will engage the vertical portion of rod 119, and gradually permit this rod to swing back towards its normal position as it moves outwardly toward the free end of portion 128. During this latter movement the arm 29 is swinging inwardly to bring the reproducer to the beginning of the record.

For the purpose of swinging the arm 29 and reproducer to starting position at the edge of the record, there is provided a friction clutch 121 having a leather friction face 126 adapted to engage the beveled friction surface on the collar 117. The arcuate friction surface 126 terminates in the reduced portion indicated by 126a so that there will be frictional engagement of the clutch only throughout the predetermined length of the friction surface 126. Thus, while the arm is being swung outwardly the clutch will in effect be released since there will be no engagement between the friction surface 126 and the drum.

But after it has reached its outward position and is ready to be swung into record engagement, the clutch, which is rotated with the shaft 61, will engage to swing the arm inwardly. When the arm is arrested at its proper position for either a ten or twelve-inch record, the friction of the clutch surfaces is overcome thereby so as to cause the clutch to slip during its continued engagement between the frictional surfaces. Thus, through this clutching action, the reproducer arm is swung inwardly with a positive and steady movement and at a speed depending upon the speed of rotation of the shaft 61. When it reaches the limit of its inward movement, the clutch merely slips until it becomes disengaged by reaching the end of the friction surface 126. As previously stated, cam 107 is eccentric and the reproducer arm starts to descend immediately after it reaches the high point 112. However, by the time extension 110 recedes from the high point, the reproducer is at the edge of the record.

For limiting the inward movement of the arm 29 under the action of the friction clutch 121, there is provided a horizontal arm 130 having a vertical extension 131 pivotally mounted in the plate 20. Secured thereto, there is a horizontal arm 132 extending under the plate 20 which is movable between the fixed pins 133 and 134, depending from said plate. Said arm is yieldingly held against the pin 134 by the spring 135 so as to normally maintain the arm 130 at its extreme outward position from the edge of the record.

The arm 130 is provided with a downwardly extending pin 136 on the end thereof, and an upwardly and forwardly extending stop member 137 on the upper side thereof having its free end spaced from said arm. Rigidly mounted on the 60 reproducer arm 29, there is a finger 138 so positioned as to engage with the member 137 when the reproducer arm is in raised position and freely pass thereunder when the arm is in lowered position. The pin 133 is so positioned that when a 65 ten-inch record is on the turntable, it will allow the arm 130 to be swung inwardly with the reproducer arm through the contact of the finger 138 with the member 137 to the proper position for lowering the reproducer into record engaging 70 position. At this point the reproducer arm will be arrested so that the reproducer is over the beginning of a record as it is lowered. Upon the reproducer being lowered into engagement with the record in its arrested position, the finger 138 75

will freely pass under the member 137 so that the reproducer will be free to move inwardly during reproduction, the arm 130 thereupon being returned to normal position by the spring 135.

- 5 When a twelve-inch record is on the turntable, the reproducer arm will swing the arm 130 inwardly until the depending pin 136 engages the edge of the twelve-inch record, whereupon the reproducer arm will be arrested and the reproducer 10 dropped into engagement with the record, freeing the finger 138 from engagement with the member 137. As above described, when the reproducer arm is arrested by the arm 130, the clutch 121 will 15 slip until released as above described. It may also be noted that the cam 107 which acts to elevate and lower the reproducer is so formed that when the reproducer swings outwardly, the finger 138 will pass over the member 137, but the reproducer arm will be lowered by the said cam surface to 20 permit engagement of the finger and said member in proper time to move the lever inwardly therewith.

Mounted on the inner side of the reproducer, there is a brush 139 supported on the end of an arm 140 which is yieldingly held in contact with the surface of the record by the spring 141. Thus, when the reproducer is lowered into record engagement, the brush which precedes the stylus will engage the reproducing grooves and not only 25 cleanse them ahead of the stylus but principally will act to gradually draw the stylus inwardly from the smooth peripheral surface of the record to groove engagement. This will prevent the stylus from slipping over the smooth peripheral 30 surface into a sudden and jarring engagement with the first groove of the record.

For instituting action of the record changing mechanism upon completion of the record, including raising of the reproducer therefrom and swinging it beyond the periphery thereof, there is provided upon the shaft 24 a peripheral lug 142 which rotates therewith. Slidably mounted upon the plate 20 and below the turntable 25 there is a bar 143 having elongated slots 144 for 35 guiding it while permitting longitudinal movement in respect to the guide pins 145. Said bar has a projection 146 adjacent the outer end thereof. The guide pins 145 are mounted upon a supporting lever 147 which is pivoted on the 40 pin 148 mounted on the plate 20. The bar 143 is yieldingly maintained at its outward position by the spring 149 connected between the free end thereof and the free end of the supporting lever 147. In frictional contact with said lever at its 45 pivotal mounting through the medium of a cork washer 150, there is an operating lever 151 having a projection extending upwardly through an 50 arcuate slot in the bracket 152 secured to the reproducer arm 29. The levers 147 and 151 are 55 yieldingly held in frictional engagement through the medium of the cork washer by the spring 153. The bar 143 has a downwardly extending projection 154 which passes through an opening in the plate 20. The lower end of said projection 60 is provided with a contact member 155 adapted to make contact with the terminal 156a, the contact therebetween closing the circuit through the 65 solenoid 58.

In operation, it will be understood that the reproducer arm moves toward the center of the record at a predetermined speed covered by the pitch of the record grooves and the speed of the turntable. Thus, upon each complete rotation of the record, the reproducer will have moved 70 inwardly toward the center of the record by an

amount equal to the pitch of the grooves. Also, during each revolution of the record, the lug 142 will strike the outer side surface of the projection 146 which will push the bar 147 over against the stop pin 156 so as to permit the lug 142 to 5 pass said projection. During the following revolution, the reproducer arm will return the bar back to normal position through the medium of the bracket 152 and levers 147 and 151. But said arm will have moved the lever back only 10 far enough by reason of the slight pitch of the record groove where the lug 142 will again engage the outer surface of the projection 146. This action will continue, i. e., lug 142 pushing the bar outwardly and passing the projection, 15 and said arm returning it again to normal position until the end of the record is reached. Thereupon, the pitch of the grooves will be suddenly and greatly increased owing to the usual eccentric or spiral groove at the end of the record. When the reproducer passes into one of those grooves, it causes said arm to throw the bar toward the lug 142 so that upon its next revolution it will not merely engage and brush by the outer surface of the projection 146, but 20 will come into full engagement with the end of the projection and force the bar rearwardly against the tension of the spring 149.

This rearward movement of the bar will complete the circuit to the solenoid 58 through the 25 contact and terminal 155 and 156a. Thus, the solenoid 58 will be energized which will act to throw the clutch members 49 and 50 into engagement and start the operation of the record changing mechanism as above described. After 30 the lug 142 has passed the projection and caused the above operation, the bar will then be brought back to normal position by the spring 149 ready for the next cycle of operation. But in the meantime, the record changing mechanism will 35 have been set into motion by the engagement of the clutch members 49 and 50, so that the reproducer is raised and swung outwardly followed by the changing, reversing or repeating of the record as above described. 45

After the coil 58 has acted to couple the clutching elements 49 and 50, the sliding beam 78 is operated by the pin 77 in the cam groove 76 to rock the pan 88. In its upward movement the pan takes the played record off the turntable by lifting it on the surface 104 if it is a 10" record, or lifting it on the surface 106 if it is a 12" record. It will be apparent that in its full line position, (Fig. 1), the pan 88 is tilting rearwardly, and the record it has taken from 50 the turntable will be dropped onto the supporting pins 44 and 45 of the rack. In the meantime, the rear record of the supply in the rack is being chopped out and dropped onto the 55 cushions or pads 75. 60

Means are provided for reversing a record whereby both sides of the record are played before the record is returned to the rack. To this end a gear 166 is secured to shaft 61, and meshes with a larger gear 167 secured on a short shaft 65 168. The relationship between gears 166 and 167 is such that gear 166 makes two complete revolutions for each complete revolution of gear 167. Shaft 168 is rotatably mounted in the frame pieces 169 and 170. 70

Slidably mounted on one end of the shaft 168 is a cam 171 having a sleeve 172 provided with a groove 173 in which engage pins 174 carried by the lower yoked end of a lever 175. At its upper end this lever is secured to a rod or shaft 75

176 extending forwardly of the machine. The rod 176 runs to the forward portion of the machine where it is operated by a control lever 157 pivoted to the plate 20 at 158. The control lever 5 is so arranged that when moved to the left, it will push the rod 176 forward. Now, when the clutching elements 49 and 50 are engaged, and the shaft 61 rotated, shaft 168 will likewise be rotated owing to the meshing gears 166 and 167. 10 During the first complete revolution of shafts 61, a new record will be fed to the turntable as previously described. However, during the second rotation of the shaft 61, that is, when a record has been played on one side, and pan 88 is moving 15 to return the record to the magazine, the cam 171 will be rotated to a position to engage and swing outwardly an arm 179 pivotally mounted on a short shaft 180.

As the arm 179 is moved outwardly by cam 171, 20 it imparts to the rod 182 a sliding movement through a housing 183. At its forward end, rod 182 (Fig. 14) is pivotally connected to an arm 184 of a member 185 including a gear segment 186. This gear segment is in mesh with a pinion 187 secured on a shaft 188 extending through the plate 20 and cut away at opposite sides at its upper end to provide a lug 189 (Fig. 2).

As rod 182 is pushed, it rotates the member 185 against the action of a spring 190 to rotate the pinion 187 and shaft 188. Also, the member 185 carries a finger piece 191 which, when the member is rotated, engages an arm 192 secured to the lower end of the rod 68. As member 192 is moved by engagement of the finger 191 therewith, rod 68 will be rocked carrying with it the reversely curved lever 64. This rod is slidably mounted on its pivot 65 (Fig. 1) and held in normal position by a coil spring 193. Thus, the lever may be caused to slide laterally on its pivot 40 on compressing this spring. Such movement of the lever will carry the roller 67 out of the path of the cam 62 so that the knife or chopping lever 72 will not be actuated to remove a record from the reservoir on the rotation of cam 62.

Above the plate 20 the stud portion 189 of the shaft 188 enters a notch in the lower end of a stud 194 journaled in a bearing 195. To the upper end of the stud 194 is secured an arm 196 offset downwardly, and at its free end carrying a reversing member 198 including a flexible plate-like portion 199 and a spring frame member 200 connected with the member 199 as at 201, and also by the spring piece 202. At its lower end, the frame-like member 200 is free of the plate-like member 199 and normally sets forwardly thereof.

When the member 185 is rotated as previously described, and rotates the pinion 187 and shaft 188, the reversing member 198 will be swung from a position at one side of the rack, in which position it slopes rearwardly, to a position in front of the rack. Now, as the pan 88 acts to return a record to the rack, the record will be disposed against the member 198, which will cause it to 65 slide back onto the turntable in reversed position owing to the fact that it cannot enter the rack. It is assisted in its sliding action by the lowering movement of the pan 88. Owing to its construction and mounting, the frame member 70 200 is resilient, and as the record is placed against it, is compressed but prevents the record from resting on the pins 44 and 45.

After the record has been returned to the turntable in reversed position, the reversing member 75 198 is swung back to its original or normal posi-

tion at the side of the rack. This may be accomplished by the spring 190. When it is desired to play a record on one side only before returning it to the rack, the lever 157 is placed at central position which will draw the rod 176 rearwardly 5 so as to disengage the cam 171 from the shaft 168. This action merely disconnects the mechanism with the reversing member so that it will not be operated and the cycle of operations by the record changing mechanism will repeat themselves 10 uninterrupted by the reversing member.

If it is desired to repeat a record, the lever 157 is moved to the right, thereby engaging through the medium of a pin 160 the beveled end of the lever 161 pivoted to the plate 20 connected with 15 the rod 162 which actuates the clutch member 163 keyed to the shaft 82. The cooperating clutch member 164 is secured to the segmental gear 84. Thus, in this position of the lever, upon the record being completed and the record changing 20 mechanism set into operation so as to raise the reproducer arm and move it into its cycle of operations for starting a new record, the pan 88 will not be operated for removing the record from the turntable, the record remaining in 25 playing position thereon to be repeated. At the same time, the movement of the lever to repeating position will actuate the rod 176 in the same manner as it is actuated when the lever is moved to the opposite side for playing both sides of the 30 record. As above described, this will cause the reversing member to swing into reversing position, but it will prevent actuation of the knife or chopping lever 72 so that the new record will not be discharged from the rack. 35

In operation, a predetermined number of records of either ten or twelve-inch diameter is placed in the rack and a record of any size placed upon the turntable. A master switch is closed to place the motor 22 in circuit with a source of 40 power, not shown herein, so that the turntable starts to rotate. The record changing mechanism and particularly the cam 62 is in such a position with the clutch members 49 and 50 in engagement that said mechanism will operate to 45 drive the clutch 121 for swinging the reproducer arm toward the record until it is stopped by engagement of the lever 132 with the pin 133 if a ten-inch record; or if a twelve-inch record, the engagement of the pin 136 with the periphery 50 of the record. Thereupon, the cam 107 will lower the reproducer into engagement with the record so as to drop the finger 138 below the member 131. The record will thereupon be reproduced.

During reproduction of the record and upon 55 each revolution thereof, the lug 142 will strike the bar 143 and pass by the same, said bar being returned by the inward movement of the reproducer the distance of the pitch of the record grooves. When the pitch is suddenly increased 60 by the eccentric or spiral inner groove, the reproducer will throw the bar so far forwardly as to cause the lug to push the same rearwardly, thereby closing the circuit through the solenoid 58. Upon the circuit being closed through the 65 solenoid, the clutch members 49 and 50 are brought into engagement. Almost immediately the circuit is broken by the spring 149 returning the bar 143 to normal position. But the undercut on the clutch teeth, coupled with the driving 70 force of the motor and resistance of the mechanism, retains said members in engagement so that the mechanism is driven through one complete revolution.

At the end of that revolution, the clutch mem- 75

bers are disconnected by the trip 42 at which time the reproducer is in record playing position and the mechanism comes to rest.

If it is desired to discharge a record before completion of its reproduction, the solenoid 58 may be energized by a push button as is well known in the art and is disclosed in the above mentioned application.

In normal position with the lever 157, in central position one side of a record will be played, whereupon the record changing mechanism will return it to the rack, remove a new record therefrom and place it upon the turntable through the action of the pan 88 and lever 72.

15 When it is desired to play both sides of a record before returning it to the rack, the lever is moved to one extreme position which will actuate the rod 176 and through said rod will swing the record reversing member in front of the rack so as to catch the record when carried to a reversing position by the pan 88, and cause the record to slide onto the turntable in reverse position. The action of this mechanism will throw the record discharging lever 72 out of operation so that a new record will not be discharged from the rack.

20 When it is desired to repeat a record, the lever 157 is thrown to the reverse position which will operate both the rod 176 and the lever 161 which acts to prevent operation of the record discharge lever 72 so that a new record will not be released from the rack, and also prevents operation of the pan 88 so that the record to be repeated will remain upon the turntable. Thereupon, the rack will swing in its normal manner, the record reversing member will swing forwardly and the reproducer will go through its cycle of movement, but other than repositioning the stylus at the beginning of the record, the record then on the turntable will not be affected.

25 The invention claimed is:

1. In a phonograph, the combination with a rotatable turntable, of a pivotally mounted magazine for retaining a plurality of records of different sizes in substantially upright position, said magazine including a back rest, a downwardly extending support for the upper edges of said records spaced from the back rest, and means for releasing a record from said support to permit it to drop against said back rest and be moved between said back rest and support whereby said record will be freed from the remaining records in the magazine and said remaining records will be supported by said support in spaced relation to said back rest.

55 2. In a phonograph, the combination with a rotatable turntable, of a pivotally mounted magazine for retaining a plurality of records of different sizes, said magazine including a back rest, means for supporting a plurality of records in substantially upright position in said magazine, means for releasing one of said records and permitting it to drop against said back rest and below the remaining records, means for elevating said released record on said back rest free from and in spaced relation to the remaining records in said magazine, and a downwardly extending support inclined toward said back rest with its lower edge spaced therefrom for supporting said remaining records in spaced relation thereto.

70 3. In a phonograph, the combination with a rotatable turntable, of a pivotally mounted magazine for retaining a plurality of records of different sizes, said magazine including a back rest, a plate upon which said magazine and turntable are mounted, a well extending below the level of

said plate, means for releasing a record from said magazine for permitting it to drop into said well, and means for raising said released record from the well on said back rest in spaced relation to the remaining records. 5

4. In a phonograph, the combination with a rotatable turntable, of a pivotally mounted magazine for retaining a plurality of records of different sizes, said magazine including a back rest, a plate upon which said turntable and magazine 10 are mounted, a well extending below the level of said plate, a downwardly extending support against which the upper edges of the records are adapted to rest in spaced relation to said back rest, means for releasing a record from said magazine to drop into said well free from said downwardly extending support and the remaining records supported thereby, and means for elevating said released record on said back rest behind said downwardly extending support. 20

5. In a phonograph, the combination with a turntable and reproducer, of mechanism for automatically disengaging said reproducer from the record, including a member for initiating the actuation of said mechanism, means for striking 25 said member periodically in timed relation to the movement of the turntable, and means connecting said member with said reproducer for returning it to position to be ineffectively struck by said means upon the reproducer being moved 30 a predetermined distance by the pitch of the reproducing grooves of the record, and effectively struck by said means for initiating the actuation of said mechanism upon being moved to a greater distance by the greater movement of 35 said reproducer upon reaching record grooves having a greater pitch.

6. In a phonograph, the combination with a turntable and reproducer, of mechanism for automatically disengaging said reproducer from the 40 record, including a member movable toward and away from the center of said turntable, means on said reproducer for moving it toward said turntable during each revolution thereof to the extent of the pitch of the reproducing grooves, 45 and means for moving it away therefrom periodically in timed relation to the movement of said turntable, said member and last mentioned means being so related as to cause engagement thereof for initiating the actuation of said mechanism 50 upon said member being moved by said reproducer a greater distance toward the center of said turntable through an increase in pitch of the record grooves.

7. In a phonograph, the combination with a 55 turntable and reproducer, of means for automatically disengaging said reproducer from the record, including a pivoted member, means on said member for initiating the actuation of said mechanism, means for causing said reproducer 60 to move said member toward the center of the turntable the distance of the record groove pitch in each revolution of the turntable, and a projection for engaging and swinging said member outwardly therefrom periodically in 65 timed relation to the movement of said turntable, said projection and initiating means being so related as to interlock and cause the disengagement of the reproducer upon said member being moved a greater distance by the 70 reproducer through engagement with the record grooves of greater pitch.

8. In a phonograph, the combination with a turntable and reproducer, of means for automatically disengaging said reproducer from the rec- 75

ord, including a pivoted lever, means for frictionally connecting said lever with the reproducer for moving it inwardly toward the center of said turntable therewith, a bar slidably mounted upon said lever provided with a projection thereon, and a lug adapted to engage with said projection for forcing said bar and lever outwardly periodically in timed relation to the movement of the turntable when returned by the frictional engagement thereof to a predetermined position governed by the pitch of the record grooves, said projection and lug being so related as to interlock upon said lever being moved inwardly to a greater distance by grooves of greater pitch, whereby said lug will force the bar to slide upon said lever and initiate the actuation of said mechanism upon completion of the record.

9. In a phonograph, the combination with a turntable, and a reproducer including a reproducer arm, of means for positioning said reproducer at the beginning of a record of any size, comprising means for elevating said reproducer above the level of the record on the turntable and lowering it into engagement therewith, means for swinging said reproducer outwardly beyond the periphery of said record and returning it toward the periphery thereof, a pivot lever positioned in the path of the reproducer adapted to be engaged thereby and moved toward the periphery of the record, a projection on said lever for engaging the periphery of the record so as to arrest the inward movement of the reproducer thereabove, said lever and reproducer being adapted to become disengaged upon lowering of the reproducer into engagement with the record, and means for swinging the lever away therefrom upon said disengagement.

10. In an automatic phonograph, the combination with a rotatable turntable, of a magazine for containing a plurality of records in substantially upright position, of means for engaging the peripheral edges and supporting said records in said magazine, a member for ejecting one of said records therefrom for transfer to said turntable, and means associated with said ejecting member for engaging a plurality of records adjacent the lower edge of the record to be ejected for moving them to ejecting position.

11. In an automatic phonograph, the combination with a rotatable turntable, of a magazine for containing a group of records supported upon their lower edge in substantially vertical position, an ejector for engaging and ejecting the record at one end of the group, and means associated with said ejector for simultaneously engaging the peripheral edge of an adjacent record and moving it into position to be next ejected.

12. In an automatic phonograph, the combination with a rotatable turntable of a magazine for containing a group of records supported upon their lower edge in substantially vertical position, an ejector for engaging and ejecting the record at one end of the group, and a hook-like member mounted on said ejector adapted to hook under one or more adjacent records for raising them with the ejecting movement of the ejector and causing them to follow the ejected record into ejecting position.

13. In an automatic phonograph, the combination with a turntable, of a magazine for containing a plurality of records therein, mechanism for transferring records from said magazine to the turntable for reproduction and from the turntable to the magazine after reproduction, whereby said

mechanism will normally return a record to the magazine after reproduction of one side thereof in reversed position for causing the reverse side of said record to be played after having passed through said magazine and returned to the turntable, means associated with said mechanism and operable to immediately reverse said record for causing the reverse side thereof to play before passing through said magazine, means for rendering said record changing mechanism and reversing means inoperative for causing the record on said turntable to be repeated, and a single manually operated lever operatively connected with said transfer mechanism and reversing means, said lever being movable to connect said reversing means and said mechanism for immediately reversing the record, and movable to another position for rendering said mechanism inoperative for repeating the record.

14. In an automatic phonograph, the combination with a turntable, of a magazine for containing a plurality of records therein, mechanism for transferring records from said magazine to the turntable for reproduction and from the turntable to the magazine after reproduction, where-
by said mechanism will normally return a record to the magazine after reproduction of one side thereof in reversed position for causing the reverse side of said record to be played after having passed through said magazine and returned to the turntable, means associated with said mechanism and operable to immediately reverse said record for causing the reverse side thereof to play before passing through said magazine, means for rendering said record changing mechanism and reversing means inoperative for causing the record on said turntable to be repeated, and manually operated means for controlling said mechanism and reversing means, whereby said reversing means may be rendered inoperative to permit a record to return to the magazine upon the playing of one side thereof, or rendered operative for reversing a record to immediately play the opposite side thereof, or render said record changing mechanism inoperative to repeat the record on the turntable.

15. In a phonograph, the combination with a turntable and reproducer, of mechanism for automatically disengaging said reproducer from the record, including a member movable in opposite directions, means associated with said reproducer for moving it in one direction during each revolution of said turntable to the extent of the pitch of the reproducing grooves on said record, and means for moving said member in the opposite direction periodically in timed relation to the movement of said turntable, said member and last-mentioned means being so related as to cause engagement thereof for initiating the actuation of said mechanism upon said member being moved by said reproducer a greater than normal distance by an increase in the pitch of the record grooves.

16. In a phonograph, the combination with a turntable and reproducer of, mechanism for automatically disengaging said reproducer from the record, including a pivoted member, means for causing said reproducer to move said member in one direction the distance of the normal record groove pitch on each revolution of the turntable, and a projection for engaging and swinging said member in the other direction periodically in timed relation to the movement of said turntable, said projection and member being so related as

to initiate the actuation of said mechanism upon said member being moved to a greater than normal distance by the reproducer through engagement with record grooves of greater pitch.

5 17. In a phonograph, the combination with a turntable and reproducer, of mechanism for automatically disengaging said reproducer from the record, including a member, means for moving said member in one direction to the extent 10 of the normal pitch of a spiral groove on the record being reproduced, means for periodically moving said member in the other direction in timed relation to the movement of the turntable, and means associated with said member for actuating said mechanism upon the movement of said member being greater than the extent of said normal pitch of the record groove in said first-mentioned direction.

18. In a phonograph, the combination with a 20 turntable and reproducer, of mechanism for automatically disengaging said reproducer from the record, including a pivotally mounted arm frictionally actuated by the reproducer to move therewith in traversing the spiral groove of normal pitch on the record being reproduced, means periodically operated in timed relation to the movement of said turntable for moving said member in the opposite direction against the frictional resistance caused by movement of the reproducer, and means for actuating said mechanism upon said member being moved through the 30 medium of the reproducer operating in a section of the record groove having a greater pitch than normal to an extreme position between its said periodic movements.

19. In a phonograph, the combination with a turntable and reproducer, of mechanism for automatically disengaging said reproducer from the record, including a member for initiating the 40 actuation of said mechanism, an element periodically striking said member in timed relation with the rotation of said turntable, and means connecting said member and reproducer for moving said member into position to be ineffectively struck by said element when the reproducer is normally moved by the reproducing grooves of the record and for moving the member into position to be effectively struck by said element for initiating the actuation of said mechanism when

the reproducer is moved abnormally by entering that portion of the groove having a greater than normal pitch.

20. In a phonograph, the combination with a turntable and reproducer, of mechanism for automatically disengaging said reproducer from the record, including a striking element movable with the movement of said turntable, a movable member adapted to be in position to be periodically struck by said element, a yielding connection between said movable member and reproducer for moving the member in a direction toward the path of movement of the striking element as the reproducer is moved by the normal pitch of the record groove, the relative positions of said striking element and movable member being such that said element will cause said member to be returned in a direction opposite to said first-mentioned direction when said member has been moved by the normal pitch of the groove and 20 said element will move said member in a different direction when said member has been moved a greater distance by the terminal groove of a record having a greater pitch, and means controlled by said member in its movement in the last- 25 mentioned direction for actuating said mechanism.

21. In a phonograph, the combination with a turntable and reproducer, of mechanism for automatically disengaging said reproducer from the record, including a striking element movable with the movement of said turntable, a member movable toward and away from the path of movement of said element adapted to assume two positions in said path, in the first of which positions it will be moved from said path when struck by said element and in the second of which it will be moved in another direction when so struck, means controlled by the movement of said member in the last-mentioned direction for initiating the actuation of said mechanism, and a yielding connection between the reproducer and said member for moving the same only to said first position as the reproducer moves through the recording groove of normal pitch and to the 45 second position when the reproducer is moved by the terminal groove of greater pitch.

EDWARD E. COLLISON.
RALPH R. ERBE.
